UNITED STATES PATENT OFFICE.

LONGFELLOW J. DAFT, OF SEATTLE, WASHINGTON.

MINE DRILLING AND CHANNELING MACHINE.

1,108,342.

Specification of Letters Patent. Patented Aug. 25, 1914.

Application filed June 23, 1913. Serial No. 775,270.

To all whom it may concern:

Be it known that I, LONGFELLOW J. DAFT, citizen of the United States, residing at Seattle, in the county of King and State of Washington, have invented a certain new and useful Improvement in Mine Drilling and Channeling Machines, of which the following is a specification.

My invention relates to improvements in mining drill machines and more particularly to improvements in drilling machines embodying a piston drill mounted upon a post or supporting column that is rigidly secured in position in a mine, and the objects of my invention are to provide suitable means for controlling the variations in the angular position of the cutting-tool rod of a drill whereby such cutting-tool rod may be directed to cut channels in different planes in the walls of a mine, and to provide improved means for attaching the drill mechanism to the supporting post. I attain these objects by devices illustrated in the accompanying drawings, wherein—

Figure 1, is a view in side elevation of a device embodying my invention, Fig. 2, is a plan view of the same on broken line x, x' , of Fig. 1, in which certain parts are broken away to better illustrate certain other parts, and Fig. 3 is an end elevation of the same on the line y, y' of Fig. 2.

Like reference numerals indicate like parts throughout the drawings.

Briefly a structure containing my invention may consist of a cutting tool attached to a piston that is adapted for reciprocal movements within a cylinder, such movements being controlled by a suitable valve, the rear end of the cylinder being provided with a ratchet member, pawls and rifle bar of usual construction for rotating the piston and cutting-tool. The cylinder is mounted in the casing in such manner that it may be fed forward toward the coal, and the casing is so attached to a post that it may be turned horizontally thereabout by means of a rotary engine adapted to have air delivered to it in intermittent puffs from the main cylinder of the drill.

Obviously, a machine embodying my invention may be advantageously employed for mining coal and other minerals or cutting rocks and other hard material.

Referring to the drawings, 5 is a post or supporting column of ordinary construction, which is adapted by suitable means to have

its ends firmly compressed against the floor and roof of a mine, rigidly to secure it in a vertical position. A two part lower sleeve composed of the segments 6 and 7, is rigidly clamped to the column 5 by bolts 8, 8 which are each pivotally mounted in the segment 6 and are each adapted to fit between two lugs 9, 9 on the segment 7 and to be secured in position by nuts 10, 10 which screw down on the lugs 9, 9. A two part upper sleeve, composed of segments 11 and 12 is rotatably mounted upon the post 5, directly above said lower sleeve and is held in position by bolts 13, 13, which bolts 13, 13 are each pivotally secured to the segment 11 and are adapted to fit between the lugs 14, 14 provided on the segment 12 and may be secured in their proper positions by nuts 15, 15 which screw down on the lugs 14, 14. The segment 11 is provided with a clamping device 16 which is recessed to fit over a conically shaped disk 17 provided on one side of a drill casing 18, as shown in Fig. 2, which drill casing 18 is adapted to carry a drill cylinder 19. The disk 17 is secured in the recessed clamping device 16 by a pawl 20 which may be clamped against the back face of the disk 17 by means of a bolt 21, to prevent said disk 17 from turning in the recessed clamping device 16. The segment 11 is provided with a semicircular worm gear 22 on its bottom end portion which is adapted to be engaged by a worm 23 journaled in suitable bearings 24 provided on a bracket 25 of the lower sleeve 6. A rotary engine 26 also mounted on the bracket 25 and having its main shaft directly connected with the worm 23 is adapted to be actuated by air communicated to it from the drill cylinder 19 through an air hose 27 and is provided with a reversing gear 28 by means of which its direction of rotation may be reversed. The drill cylinder 19 is slidably mounted in the casing 18 by means of V shaped bearings 29, 29, as shown in Fig. 3, provided on each of its sides and is adapted to be longitudinally adjusted and held therein by a feed screw 30, the inner end of which feed screw 30 screws into a threaded hole provided in the drill cylinder 19, its outer end being provided with a crank-handle 31 which is suitably journaled in the outer end of a bracket 32 provided on the cylinder casing 18 by which crank-handle 31, the said feed-screw 30 may be rotated. The drill cylinder 19 is provided with a valve chest 33 having a suitable

air connection 34, and is further provided with suitable exhaust ports 35, 35, and with a reciprocating piston (not shown) to which is attached a piston rod 36, which piston rod 36 is connected with a drill rod 37, carrying a drill point 38, on its outer end.

The operation of my drill machine may be described as follows. The device is set up in a mine with the post 5 approximately vertical and the drill point 38 in a desired position with respect to the face of the rock or coal that is to be cut. Air under pressure is admitted to the valve chest 33 through the air hose 34 from whence it is admitted to the cylinder 19 through suitably arranged and valve-controlled ports to cause the piston to reciprocate, thus to cause the drill point to strike blows on the face of the mineral to cut it away. When the piston is at the forward end of the cylinder it laps the air tap 39 thus closing said tap 39 and cutting off the compressed air supply from the rotary engine 26 that is connected with the cylinder 19 by the air hose 28, but when the piston 25 moves toward the opposite end of the cylinder it opens the air tap 39 and permits air to flow through the hose 28 to actuate the rotary engine 26 and turn the worm 22.

The rotary engine 26 thus may receive an impulse on each backward stroke of the piston and the worm 23, to which this impulse is transmitted, act upon the worm gear 22 to move it through a small part of a revolution each time, thus to rotate the drill cylinder slightly about the post 5 and to move the cutting tool a short distance horizontally along the cut in the face of the mineral from which new position it may strike another blow as the piston is again driven to the front end of the cylinder. Air is thus taken from the cylinder through the hose 28 and delivered to the rotary engine 26 in a series of intermittent puffs is delivered to said engine to actuate the drill mechanism during the time that the cutting-tool is withdrawn from the mineral, and the mechanism is so arranged that air is cut off from the engine 26 before the cutting-tool strikes its blow, so that said cutting tool shall not be moving horizontally when it strikes the face of the mineral.

The rotary engine 26 is provided with a reversing gear 28 by means of which the cutting-tool 38 may be reversed and thus cause said cutting-tool to oscillate forth and back across the face of the mineral by intermittent steps to cut a horizontal channel in the face of the mineral. If it be desired to make a vertical cut in the face of the coal the

rotary engine 26 may be disconnected and the pressure of the pawl 20 so regulated by releasing the tension on the bolt 21 that the drill mechanism may be oscillated vertically by hand.

Manifestly, minor changes in the details and construction of my device may be made within the scope of the appended claims without departing from the spirit of my invention or sacrificing any of its advantages.

What I claim is:

1. In a mining drill, the combination with a supporting column, of a lower two-part sleeve rigidly clamped to said column, a two-part upper sleeve rotatably-mounted on said column, a drill casing provided on one side with a conical disk, a clamp carried by said upper sleeve and recessed to receive said disk, a drill cylinder carried by said casing, a motor supported adjacent to said lower sleeve, an air conduit for said cylinder, an air conduit connection between said cylinder and motor, a drill carried by the piston-rod of the drill cylinder, and means for rotating said cylinder about said column when the drill is withdrawn.

2. In a mining drill, the combination with a supporting column, of an upper and a lower sleeve on said column, said lower sleeve being rigidly clamped upon the column, and said upper sleeve rotatably-mounted thereon, a drill cylinder carried upon the upper sleeve, a motor supported adjacent to the lower sleeve, worm gearing interposed between said rotatable sleeve and motor and driven by the latter to rotate said cylinder about the column by successive movements of the motor shaft.

3. In a mining drill, the combination with a supporting column, of a lower sleeve fixed upon the column, an upper sleeve rotatably-mounted on said column and formed with worm gearing, a drill cylinder carried by said upper sleeve, a motor supported adjacent to said lower sleeve, a worm wheel driven by said motor and meshing with said gearing to impart intermittent rotary movement to said cylinder around the column, and an air conduit connecting said motor and drill cylinder whereby the motor is operated on the backward movement of the piston rod of the cylinder.

In witness whereof, I hereunto subscribe my name this 23rd day of May A. D., 1913.

LONGFELLOW J. DAFT.
